LOOP WARP TENSION-VARIABLE BEAT-UP APPARATUS FOR TERRY LOOMS

Theodore C. Sippel, Rock Hill, S. C., assignor to
Edinburgh Corporation, Laurinburg, N. C., a
corporation of North Carolina

Application September 25, 1950, Serial No. 186,531

3 Claims. (Cl. 139—26)

1

This invention relates to looms for weaving looped fabrics, such as terry fabrics and the like, and more especially to an improved pattern controlled variable beat-up mechanism wherein the position of the reed is varied upon predetermined beat-up strokes of the lay and also includes pattern controlled means for effecting a momentary slackening of the tension in the loop warp yarns, the pattern means serving to cause a coacting relationship between the periods in which a variation of the beat-up of the reed and a variation in the tension in the loop warp yarns is effected.

It is an object of this invention to provide an apparatus of the type described which is comprised of a minimum of parts and requires only minor changes in the loom structure and wherein the variable beat-up mechanism and the means for slackening the tension in the loop warp yarns may be controlled from a common pattern mechanism such as a dobby head or a jacquard mechanism.

It is still another object of this invention to provide an improved pattern controlled means for stopping the reed in the course of a beat-up stroke of the lay at predetermined intervals in advance of the lay reaching the limit of its movement toward the normal fell of the cloth, the reed being pivotally mounted upon the lay to permit the lay to continue its movement after the reed has been stopped. The improved means for stopping the reed in advance of the lay approaching the normal limit of its forward movement includes crank means pivotally mounted intermediate the upper and lower ends of the swords which support the lay and having arms extending at substantially right angles to each other, one of the arms having the front end of a forwardly and rearwardly movable traverse bar connected thereto provided with a notch therein and the other or others of the arms each having a connecting rod pivotally connected to the free end thereof. The other end of each connecting rod is connected, by means of a toggle leverage, to the lower edge of a reed which is pivoted with the reed cap so the lower edge thereof may move relative to the sword.

A latch is pivoted adjacent the traverse bar and is connected to a pattern mechanism which will cause the latch to engage the notch in the traverse bar at predetermined intervals upon a forward or beat-up stroke of the lay thus causing the traverse bar to impart movement to the 55 arms pivoted on the swords to, in turn, cause the

2

lower edge of the reed to swing rearwardly relative to the lay so that the reed will stop short of a normal beat-up stroke thereof although the lay may continue through to the limit of its forward stroke.

It is still another object of this invention to provide pattern controlled means which coact with the shortening of the beat-up stroke of the reed for causing an additional length of loop warp yarn to be fed to the reed or, in other words, to slacken the tension in the loop warp yarns momentarily during each normal heat-up stroke immediately following the relatively short beat-up stroke or strokes of the reed so as to permit the slackened loop warp yarns to be subsequently taken up by the reed during normal beat-up strokes therefrom to form loops thereof. This pattern controlled means for slackening or feeding the loop warp yarns includes a feed roll, preferably an abrasive roll, tightly around which the loop warp yarns pass in their course to the reed and which is geared to a ratchet wheel past which a pawl is reciprocated by mechanical connections with the driven parts of the loom, there being a connection between the pattern mechanism and the pawl for periodically moving the pawl into engagement with the ratchet wheel at predetermined intervals to thus impart movement to the ratchet wheel and the loop warp feed roll to slacken the warp yarns carried thereby momentarily.

Some of the objects of the invention having been stated, other objects will appear as the description proceeds when taken in connection with the accompanying drawings in which—

Figure 1 is a schematic longitudinal vertical sectional view through a loom for weaving looped fabrics, with many of the parts being shown schematically and showing the improved variable beat-up and loop warp feed apparatus in association therewith;

Figure 2 is an enlarged elevation looking substantially along the line 2—2 in Figure 1 and showing a medial portion of the loom and including details of the improved variable beat-up apparatus;

Figure 3 is an enlarged fragmentary elevation of the left-hand portion of Figure 1 showing the lay and associated parts in a different position;

Figure 4 is a fragmentary elevation of the upper left-hand portion of Figure 3 showing the reed in a forward position;

Figure 5 is an enlarged perspective elevation looking at the opposite side of the upper right-hand portion of Figure 1 and illustrating the

improved pattern controlled means for feeding the loop warp yarns;

Figure 6 is a fragmentary elevation looking at the right-hand side of Figure 5, omitting all but the central portion of Figure 5.

Referring more specifically to the drawings, the numeral 20 indicates the horizontally spaced side frames of a terry loom, only one of which is shown in Figure 1. These loom side frames 20 are held in spaced relation to each other by a breast beam 21, a front lower girt 22, a rear lower girt 23 and an arch 24 all of which are suitably secured in the usual manner to the loom side frame members 20. Supported in a conventional manner on the loom side frame members 20 and being provided with the usual warp tension means associated therewith, not shown, is a basic warp beam 25 disposed above which is a loop or terry warp beam 26.

The basic warp beam 25 has base warp yarns W-1 extending upwardly and forwardly therefrom which pass over a suitable roll 27, which may be termed a whip roll. These base warp yarns W-1 extend forwardly from above the whip roll 27 and pass through a pair of relatively vertically movable harnesses 30 (Figures 1 and 3) to which movement is imparted from a driven crank shaft 31 rotatably mounted on the loom side frame members 20 and through intervening conventional connections, not shown, but which are well known to those familiar with the art.

The base warp yarns W-1 pass forwardly from the harnesses 30 and through a pivoted or swingable reed 34 the upper edge of which is fixedly mounted in a conventional pivoted reed cap 35 and the lower end of which is mounted in a loose reed bar 36 which is disposed in a notch provided therefor in a conventional lay 37. The lay 37 and the reed cap 35 are supported in a conventional manner on swords 40, only one of which is shown in Figures 1, 2 and 3. The lower ends of the swords 40 are pivotally supported for rocking movement on a conventional rocker shaft 41.

Oscillation is transmitted to the lay 37, reed 34, and reed cap 35 from a conventional crank shaft 42 which is driven in a conventional manner and which is provided with crank throws 43 to which the rear ends of conventional pitman rods or arms 44 are pivotally connected. The front ends of the pitman arms 44 are pivotally connected to the corresponding swords 40. It is thus seen that oscillation is imparted to the swords 40, the lay 37, the reed 34 and the reed cap 35 upon each revolution of the crank shaft 42. The base warp yarns W-1 extend forwardly from the reed, as shown in Figure 1, and converge at a beat-up point indicated at B at which point the weft yarns are beat-up with the warp yarns to form terry fabric indicated at F which then extends to a suitable take-up means including a sand roll 47.

The loop warp beam 26 has loop warp yarns W-2 extending downwardly therefrom in Figure 1 which are preferably of substantially greater diameter than the base warp yarns W-1 and are also of a relatively lighter twist. These loop warp yarns W-2 extending beneath and partly around an improved loop warp feed control roll 50 opposed ends of which are rotatably mounted in bearing blocks 51, only one of which is shown on the corresponding loom side frame 20 (Figures 5 and 6). The manner in which this roll 50 controls the slackening or feeding of the loop warp yarns W-2 will be later described.

In order to insure traction of the loop warp yarns W-2 against the periphery of the roll 50, this roll 50 is preferably provided with an abraded surface and also is engaged by an idler roll 52 over which the loop warp yarns W-2 also pass subsequent to their passing beneath the roll 50. The loop warp yarns W-2 then extend downwardly past guide rods or rolls 53 and 54, successively, from whence they extend forwardly and are interspersed between some of the base warp yarns W-1 as the loop warp yarns pass forwardly, they pass through a plurality of heddles 55 to the lower end of each of which a corresponding weight or lingo 56 is connected as is clearly shown in Figure 2. These heddles 55 depend from cords which extend through a comb board 57 and thence to a suitable pattern mechanism such as a jacquard, not shown, but which may be of a double lift type such as is shown in United States Patent No. 802,938.

It is evident that the loop warp yarns W-2 extend forwardly from the heddles 55 and pass through the reed 34 to be beat-up into the fabric F. Of course, the conventional take-up means embodied in the sand roll 47 serves as a normal take-up means for said loop warp yarns W-2 as they are interwoven to form the fabric F. The parts heretofore described are conventional parts of the usual type of loom for weaving terry fabrics and it is with these parts that the present invention is adapted to be associated.

Since the primary object of this invention is to provide coacting pattern controlled means for varying the effective beat-up stroke of the reed 34 and to momentarily excessively feed the loop warp yarns to the reed 34, a description will first be given of the means for varying the effective beat-up stroke of the reed 34.

Referring to Figures 1, 2 and 3, it will be observed that the swords 40 each has a bearing block 60 suitably secured thereto, only one of which is shown in the drawings. These bearing blocks oscillatably support a pivot shaft 61 to which the rear ends of a plurality of laterally spaced first crank arms 62 are fixedly secured, only one of these arms being shown in the drawings. These arms 62 extend forwardly and upwardly at a slight angle relative to the horizontal.

Also, fixed on the pivot shaft 61 is the upper end of a second crank arm 64 which extends at substantially right angles to the crank arms 62 and is provided with an adjustment slot 65 to which the front end of a traverse bar 66 is adjustably and pivotally connected. The traverse bar normally has forward and rearward movement in a substantially horizontally disposed tubular guide member 70 pivotally connected at its rear end, as at 71 (Figures 1 and 3), to a block 72 suitably secured to the rear lower girt 23.

The upper wall of the tubular guide member 70 is notched as at 73 so the free end of a pivoted latch or pawl 75 may, at times, enter the notch 73 to bear against the upper surface of the traverse bar 66. This latch 75 is pivotally mounted intermediate its ends, as at 76, on a suitable support 77 projecting upwardly from opposed sides of the tubular member 70.

According to the desired pattern, the latch 75 is urged into engagement with the upper surface of the traverse bar 66 during a forward stroke of the swords 40. The traverse bar 66 has a notch 80 in the upper edge thereof which is then engaged by the latch 75 to thus prevent further forward movement of the traverse bar 66. This will cause the crank arms 62 and 64 to rotate the shaft 61 a partial revolution for changing

the position of the reed 34 relative to the lay 37 in a manner to be later described.

The latch 75 has a connecting rod or wire 82 connected to the rear end thereof which is bent so as to miss the cam shaft 31 and the upper end of which is resiliently connected, as by a tension spring 83, to the lower end of a cord 84 which is the usual part of a jacquard pattern mechanism. The purpose of the resilient connection 83 between the connecting rod or wire 82 and the cord 84 is to permit the cord 84 to continue its upper movement after the working end of the latch 75 has engaged the traverse bar 66 and to thus insure that the latch 75 will subsequently be urged into the notch 80 in the traverse bar 66.

The lower end of a longitudinally adjustable link 86 is pivotally connected, as at 87, to the front free end of each of the first crank arms 62. A tension spring 90 is connected at its lower end intermediate the ends of each link 86, its upper end being suitably connected to the lay 37. This tension spring 90 normally urges the link 86 upwardly thus normally urging the crank arms 62 and 64 and the pivot shaft 61 in a clockwise direction to assume substantially the position shown in Figure 1 relative to the swords 40. It is evident that upon the latch 75 engaging the notch 80 of the traverse bar 66, the tension in the spring 90 will be overcome to permit the crank arms 62 and 64 to rotate in a counter-clockwise direction in Figure 1.

The upper end of each link 86, only one of which is shown in Figures 1, 2, 3 and 4, is pivotally connected to a projection 93 depending from one end of a corresponding toggle link 94. Each toggle link 94 is connected at its front end to a toggle support 91 and its rear end is connected to the front end of a second toggle link 95 which straddles the same. The rear end of each toggle link 95 is pivotally connected to the lower end of a corresponding lever 96 which it also straddles.

Each lever 96 is oscillatably mounted intermediate its ends, as at 100, on the outer end of a block 101 suitably secured to the lay 37. The upper end of each lever 96 is pivotally connected as at 102, to the rear edge of the loose reed bar 36. It is preferable that a group of each of the parts 62, 86, 87, 90, 91, 93 to 96, 100, 101 and 102 is provided adjacent each of the side frame members 20 and at the middle of the lay 37 in order to adequately control the position of the loose reed bar 36 throughout its length.

A conventional protector rod 38 is rotatably mounted in bearing blocks 39 beneath the lay 37, against which the junction of the toggle links 94 and 95 is normally urged by the tension spring 90. Referring to Figure 4, it will be noted that the junction of the toggle links 94 and 95 is against the protector rod 38 and is off-center in order to lock the toggle links 94 and 95 in position until downward pressure is applied to the link 86, whereupon the toggle links 94 and 95 move to the position shown in Figure 3.

Now, as heretofore stated, when the loose reed bar 36 is disposed in substantially the position shown in Figure 1 relative to the lay 37, a normal beat-up stroke will be transmitted to the reed 34 from the lay 37 and the reed cap 35 upon each beat-up stroke thereof. However, when the pattern means from which the cord 84 extends moves the latch 75 into operative position for engaging the notch 80 on the traverse bar 66, the crank arms 62 and 64 move in a counterclockwise direction relative to the swords 40 and will cause 75

each connecting link 86 to move downwardly. This will result in the corresponding toggle links 94 and 95 moving downwardly at their proximate ends to thus move each lever 96 in a clockwise direction in Figures 1 and 4.

This will result in the loose reed bar 36 swinging partially out of the notch provided therefor in the lay 37 and thus, the reed 34 will stop short of a normal beat-up stroke thereof (see Figure 3) 10 while the lay 37 continues to the forward limit of its normal beat-up stroke.

It is thus seen that I have provided an improved pattern controlled means for varying the position of the reed 34 relative to the lay 37 upon 15 predetermined beat-up strokes thereof. Operating in conjunction with the pattern controlled means for varying the position of the reed 34 relative to the lay 37, is a pattern controlled means for imparting rotation to the loop warp feed control roll 50 at a speed faster than the normal speed imparted thereto by the take-up means embodied in the sand roll 47.

Referring to Figures 5 and 6, it will be observed that there is a pinion 105 fixed on one end of the 20 roll 50 and which meshes with a gear 106 having a ratchet wheel 107 integral therewith. The ratchet wheel 107 and the gear 106 are rotatably mounted on a stub shaft 110, one end of which is fixedly secured in the bearing block 51. The bearing block 51 is suitably secured to a vertically disposed frame member 111 which extends 25 downwardly and is secured to the left-hand side frame member 20.

Also, oscillatably mounted on the stub shaft 35 110 is a bell crank 112 having an upwardly extending arm 113 integral therewith on which a ratchet pawl 114 is pivotally mounted intermediate the ends thereof. The outer end of this ratchet pawl 114 has one end of a flexible cord 115 connected thereto. The pawl 114 is normally urged in a counterclockwise direction in Figure 6 by a tension spring 116. However, the rear end of the pawl 114 may be made heavy enough to over-balance its front end, instead of 40 using the spring 116, to normally urge the front end of the pawl 114 upwardly to inoperative position, if desired. This cord 115 extends inwardly in substantially parallel relation to the horizontal portion of the arch 24, after passing upwardly through a suitable eye 117 extending 45 inwardly from the arm 113 of the bell crank 112, and also extends towards the observer in Figure 1 and is then passed beneath a rod 120 extending rearwardly from the horizontal portion of the arch 24. The cord 115 is then resiliently connected, 50 as by a tension spring 121, to the lower end of a cord 84a which is also a part of the jacquard mechanism.

Now, upon each beat-up stroke of the lay 37, 55 the bell crank 112 is caused to oscillate so as to move the ratchet pawl 114 past or in engagement with the ratchet wheel 107. According to the patterning of the pattern mechanism, not shown, the cord 84a will move upwardly subsequent to 60 certain relatively short beat-up strokes of the reed 34 thus causing the ratchet pawl 114 to move into engagement with the ratchet wheel 107 and, upon each reciprocation of the bell crank 112, a step in rotation will be imparted to the feed roll 50 at a faster rate than the loop warp yarns W-2 are normally pulled thereby 65 through normal operation of the conventional take-up means embodied in the sand roll 47. This will result in the loop warp yarns W-2 being slackened during the initial normal beat-up

stroke or strokes following each relatively short beat-up stroke or series of relatively short beat-up strokes of the reed and, thus, these slackened loop warp yarns will be piled up by the several picks of weft yarn being carried forward together to the fell of the cloth or fabric F by said initial normal beat-up strokes of the reed, resulting in loops being formed of the lengths of loop warp yarns fed at a faster than normal rate by the feed roll 50.

Oscillation is imparted to the bell crank 112 by means of a cam 120 (Figures 1 and 5) fixed on the cam shaft 31 which engages a forwardly and rearwardly extending arm 121 pivoted at one end on the corresponding loom side frame member 20 and the rear end of which is pivotally connected to the lower end of a longitudinally adjustable connecting rod or link 122. The connecting rod 122 extends upwardly and is pivotally connected, as at 123, to the free end of an arm 124 of the bell crank 112, this arm 124 extending at substantially right angles to the arm 113 heretofore described.

It will be observed, in Figure 6, that a hold-back pawl 125 rests against the teeth of ratchet wheel 107 and is pivoted on the frame member 111 so as to prevent unintentional reverse movement of the feed roll 50. However, it is evident that this hold-back pawl 125 may be raised out of engagement with the teeth of the ratchet wheel 107 for the purpose of backing up the loop warp yarns W2 in the event of an imperfect fabric having been woven and necessitating that some of the weft yarns be picked out of the fabric to be rewoven therein.

It is thus seen that I have provided pattern controlled means for controlling the feeding of an excess length of the loop warp yarns at predetermined intervals to operate in coacting relationship to the means for varying the beat-up stroke of the reed 34. Although many attempts have been made to perfect an apparatus for varying the length of the beat-up stroke of the lay or reed 34 the present apparatus is of a relatively simple construction and may be easily and economically manufactured and also includes a minimum of parts which may be easily applied to looms with only slight modifications of the looms being required.

In the drawings and specifications there has been set forth a preferred embodiment of the invention and although specific terms are employed, they are used in a generic and descriptive sense only and not for purposes of limitation, the scope of the invention being defined in the claims:

I claim:

1. In combination with a loom for weaving looped fabrics and having means for taking up the fabric woven in the loom, said loom having an oscillatable lay and also having a reed cap pivotally supported in spaced relation to the lay and also having a reed supported by the reed cap for pivotal movement therewith, said loom having oscillatable swords thereon for supporting the lay and the reed cap and means for directing loop warp yarns to said reed; pattern controlled means for swinging the reed to occupy different positions relative to the lay upon certain beat-up strokes thereof comprising a lever pivoted on the lay and being pivotally connected at one end thereof to the reed, a toggle leverage means pivotally connected to the other end of the lever, a traverse bar, a tubular member pivotally supported by the loom and in which the traverse bar is adapted to have longitudinal movement, said traverse bar

having a notch therein, pattern controlled latch means carried by the tubular member for engaging the notch in the traverse bar at predetermined intervals, a pivot shaft oscillatably supported intermediate the ends of the swords, at least one first crank arm fixedly mounted on said pivot shaft, the free end of the first crank arm having a mechanical connection with said toggle leverage means, a second crank arm fixed on the pivot shaft and to which one end of the traverse bar is pivotally connected and spring means normally holding the second crank arm in such a manner as to cause a normal beat-up stroke to be imparted to the reed upon each beat-up stroke of the lay whereby, upon said latch means engaging the notch in the traverse bar, the traverse bar will cause the second crank arm to which it is connected to rotate the pivot shaft during forward movement of the swords to, in turn, impart movement to the first crank arm and the toggle leverage means and thus to the lever for swinging the reed rearwardly relative to the lay upon a beat-up stroke thereof to cause the reed to beat-up the weft yarn in spaced relation to a previously beat-up weft yarn.

2. An improvement in a loom for weaving looped fabrics, said loom having means for taking up the fabric woven in the loom, said loom having an oscillatable lay and also having a reed cap pivotally supported in spaced relation to the lay and also having a reed supported by the reed cap and said loom also having oscillatable swords thereon for supporting the lay and means for directing loop warp yarns to said reed; said improvement comprising pattern controlled means for swinging the reed to occupy different positions relative to the lay upon certain beat-up strokes thereof including a first lever pivoted on the lay and being pivotally connected at one end thereof to the reed, at least one pair of toggle levers pivotally connected to each other at their proximate ends, the free end of one of the toggle levers being pivotally connected to the lay and the free end of the other toggle lever being pivotally connected to the first lever, a traverse bar, a guide member pivotally supported by the loom and in which the traverse bar is adapted to have longitudinal movement, said traverse bar having a notch therein, pattern controlled latch means carried by the guide member for engaging the notch in the traverse bar at predetermined intervals, at least one first crank arm pivotally supported at one end intermediate the ends of the swords, the other end of the first crank arm having one end of a link pivotally connected thereto, the other end of said link being pivotally connected to at least one of said toggle levers, a second crank arm pivoted on the swords in fixed relation to said first crank arm and to which one end of the traverse bar is pivotally connected, and resilient means normally holding the crank arms in such a manner as to cause a normal beat-up stroke to be imparted to the reed upon each beat-up stroke of the lay whereby, upon said latch means engaging the notch in the traverse bar, the traverse bar will cause the crank arms to rotate during forward movement of the swords to, in turn, impart movement to the proximate ends of the toggle levers and, thus, to the lever so as to swing the reed rearwardly relative to the lay upon a beat-up stroke thereof to thus cause the reed to beat-up the weft yarn in spaced relation to a previous normally beat-up weft yarn.

3. An improvement in a loom for weaving looped fabrics, said loom having means for taking up

the fabric woven in the loom, said loom having an oscillatable lay and also having a reed cap pivotally supported in spaced relation to the lay and also having a reed supported by the reed cap and said loom also having oscillatable swords thereon for supporting the lay and means for directing loop warp yarns to said reed, said improvement comprising pattern controlled means for swinging the reed to occupy different positions relative to the lay upon certain beat-up strokes thereof including a first lever pivoted on the lay and being pivotally connected at one end thereof to the reed, a pair of toggle levers pivotally connected to each other at their proximate ends, the free end of one of the toggle levers being pivotally connected to the lay and the free end of the other toggle lever being pivotally connected to the first lever, a traverse bar, guide means carried by the loom for guiding the traverse bar for longitudinal movement, said traverse bar having a notch therein, pattern controlled latch means for engaging the notch in the traverse bar at predetermined intervals, a support carried by the loom in fixed relation to the guide means, said latch means being movably supported by 25 said support, at least one first crank arm pivotally supported at one end intermediate the ends of the swords, the other end of the first crank arm having one end of a link pivotally connected thereto, the other end of said link being pivotally connected to at least one of said toggle levers, a

5 second crank arm pivoted on the swords in fixed relation to said first crank arm and to which one end of the traverse bar is pivotally connected, and resilient means normally holding the crank arms in such a manner as to cause a normal beat-up stroke to be imparted to the reed upon each beat-up stroke of the lay whereby, upon said latch means engaging the notch in the traverse bar, the traverse bar will cause the crank arms to rotate during forward movement of the swords, to in turn, impart movement to the proximate ends of the toggle levers and, thus, to the lever so as to swing the reed rearwardly relative to the lay upon a beat-up stroke thereof to thus cause the reed to beat-up the weft yarn in spaced relation to a previous normally beat-up weft yarn.

THEODORE C. SIPPEL.
